ELECTRICAL CONNECTION BOX

Stephen M. Vilegi, Chester, John J. Marshall and Louis H. Peters, Somerville, N.J., and Dennie Dannes and Walter J. Frank, Norwalk, Conn., assignors to Union Carbide Corporation, a corporation of New York

Filed Sept. 30, 1968, Ser. No. 13,782

Term of patent 14 years

Int. Cl. D13—03

U.S. Cl. D26—5

Fig. 1.

Fig. 2.

FIG. 1 is an isometric view of an electrical connection box showing our new design;

FIG. 2 is a top plan view of the electrical connection box of FIG. 1;

FIG. 3 is a side plan view of the electrical connection box of FIG. 1, the side opposite that shown in FIG. 3 being identical to the side shown;

FIG. 4 is a bottom plan view of the electrical connection box of FIG. 1, and

FIG. 5 is an end plan view of the electrical connection box of FIG. 1, the end opposite that shown in FIG. 5 being identical to the end shown.

We claim:

The ornamental design for an electrical connection box, substantially as shown and described.
